UNITED STATES PATENT OFFICE.

ALFRED GRIEB, OF ELIZABETH, NEW JERSEY, ASSIGNOR TO THE SINGER MANUFACTURING COMPANY, OF ELIZABETH, NEW JERSEY, A CORPORATION OF NEW JERSEY.

LABEL-SEWING MACHINE.

Application filed October 14, 1920. Serial No. 416,927.

To all whom it may concern:

Be it known that I, ALFRED GRIEB, a citizen of the United States, residing at Elizabeth, in the county of Union and State of

5 New Jersey, have invented certain new and useful Improvements in Label-Sewing Machines, of which the following is a specification, reference being had therein to the accompanying drawings.

10 This invention relates to label sewing machines, and especially to machines of the type represented by the United States patents to F. H. Chilton No. 870,543, of November 12, 1907, and W. A. Adams No.

15 1,151,846, of August 31, 1915, which are characterized by the combination with sewing means, of mechanism for preparing individual labels as needed from a continuous tape or label-strip. The Adams machine,

20 while embodying means for holding the label firmly in sewing position throughout the sewing operation, does not embody means for folding over the cut ends of the label. The Chilton machine, while embody-

25 ing label-end folding means, has no means for holding the label in sewing position relative to the fabric throughout the sewing operation.

It is understood that the term "label" is 30 herein used in its broad sense and, as so used, is intended to include a tab, patch, button or buttonhole reinforce or, in fact, any small individual piece of flexible penetrable material.

35 An object of the present invention is to provide a label-sewing machine which prepares its own labels with folded ends and feeds them to a work-holder which retains full control of the folded label until the 40 sewing is completed.

Another object of the invention is to provide a label-sewing machine with improved and simplified mechanism for feeding the label-strip, severing the labels therefrom, and feeding the severed labels to sewing position.

45 Another object of the invention is to provide for the interruption of the normal automatic feed of the label-strip when for any reason, such as defective sewing, it is desired to repeat the sewing operation upon a given label. In this connection the invention also has for an object to provide against

the release of the label in the work-holder until the operator is assured that the first 55 sewing is satisfactory and that a repetition of the sewing is unnecessary.

Still further, the invention has for an object to provide the machine with an improved work-gauge facilitating the accurate 60 placing of the patches or labels upon the garments to which they are to be applied.

In its preferred embodiment, the invention comprises a sewing machine of the type represented by the U. S. patent to C. M. 65 Horton No. 807,676, of December 19, 1905 into which has been built the label-feeding severing, folding and controlling devices hereinafter described.

It has been customary, in folded label 70 work, to provide one machine for preparing labels from a label-strip and another separate and distinct machine for sewing them to a body-fabric; the first or label-preparing machine serving to fold over the cut ends of the labels and iron them flat, so that the folded ends will not open up and interfere with the presentation of the labels by hand to the second or label sewing machine.

75 In accordance with the present improvement, label-strip feeding means, severing means, and label-end folding means have been combined in an organized machine with a work-holder which retains complete 80 control of the folded label and holds the latter firmly in sewing position relative to the fabric throughout the sewing operation; the release of the label being preferably under manual control.

85 The invention further comprises the combinations of parts and details of construction hereinafter described and particularly pointed out in the appended claims.

90 In the accompanying drawings Fig. 1 is a side elevation of the machine embodying the invention. Fig. 2 is a top plan view of the machine bed; the bracket-arm standard being sectioned. Fig. 3 is a bottom plan view of the machine. Fig. 4 is an enlarged plan view of the label-handling mechanism; the parts being in starting position. Figs. 4^a and 4^b are sections on the line 4^a—4^a and 4^b—4^b, respectively, Fig. 4. Fig. 5 is a similar view of the parts at the end of the first side-stitching operation. Fig. 6 is an enlarged section on the line 100 105

6—6, Fig. 4. Figs. 7^a and 7^b are, respectively, sections on the lines 7^a—7^a, 7^b—7^b, Fig. 4. Fig. 8 is a section on the line 8—8, Fig. 4. Fig. 9 is a reverse side view of the 5 label-severing knife shown in Fig. 8. Fig. 10 is a perspective view of the lower work-holder element, showing the opposed folding scrolls. Fig. 11 is a fragmentary longitudinal section through the lower work- 10 holder element in position upon the machine-bed. Fig. 12 is a perspective view of the under side of the label-feeder or pusher which advances the labels from the label feed-slide to the work-holder. Fig. 13 is 15 a section on the line 13—13, Fig. 4. Fig. 14 is a section on the line 14, 14, Fig. 5. Fig. 15 is a view similar to Fig. 14, but showing a label severed from the strip and gripped by the label scoring and feeding foot. Fig. 20 16 is a view similar to Fig. 15 but showing the severed and scored label released by the label feeding foot in transfer position and ready to be pushed through the folding scrolls and into the work-holder. Fig. 17 25 is a section on the line 17—17, Fig. 4. Fig. 18 is a perspective view of the three-armed lever element carrying the label-severing knife, label-gripping foot and the piercing pin which pulls the label-strip from the 30 supply; and Fig. 19 is a perspective view of a label with the ends scored preliminary to the folding operation.

The invention is preferably embodied in a machine of the well known Singer No. 68 35 button-sewer type having a frame, stitch-forming mechanism, a stop-motion device, thread-cutting mechanism and work-holder actuating mechanism constructed substantially in accordance with the disclosure of 40 the said Horton patent. The frame is formed with a flat bed 1, standard 2 and overhanging bracket-arm 3 terminating in a head 4 in which is journaled the reciprocating needle-bar 5 carrying the eye-pointed 45 needle 6 which cooperates as usual with suitable loop-taking means beneath the bed 1. In its reciprocation, the needle passes through the usual needle-hole 7 in the throat-plate 8 which is substantially flush 50 with the upper surface of the bed 1. The main-shaft 9 of the machine is journaled within and longitudinally of the bracket-arm 3 and at its rearward end carries the tight and loose pulleys 10, 11 which, together with the start- and stop-motion lever 55 12 pivoted at 12' and carrying the belt-shipper 13, constitute the usual stop-motion device for controlling the period of operation of the stitch-forming mechanism. The 60 machine is also preferably provided with the usual automatic thread-cutting mechanism 14 disposed beneath the throat-plate 8.

The work-holder comprises separable upper and lower elements carried by a work- 65 holder supporting bar 15 which extends

longitudinally of and above the bed 1. The bar 15 is moved bodily lengthwise of the bed 1 and is given a lateral pivotal movement about the axis of the post 16 at the rearward end of the bar 15 by the usual 70 trains of connections with the cam-grooves 17, 18 in the opposite faces of the feed-wheel 19. As the mechanism for so moving the bar 15 is well known, a more detailed description thereof is deemed unnecessary. 75 It will suffice to explain that the cam-grooves 17 and 18 are so designed as to move the work-holder elements at the free end of the bar 15 in the desired path. In the present embodiment of the invention, the 80 desired path is rectangular in form in order that the stitches will be placed around the four sides of a rectangular patch or label. Secured to the work-holder supporting 85 bar 15 by means of the screw 20, Fig. 5, 90 is the off-set extension 21 terminating in the lower clamp-plate 22 which rests upon the smooth upper surface of the throat-plate 8 and is adapted to slide thereover. The plate 22 is formed with a rectangular 95 label-receiving cavity c, Fig. 10, bounded by the front and rear label side edge gauging walls 23, 24, Figs. 7^a, 7^b, and label end edge gauging walls 25, 25. The lower 100 clamp-plate 22 includes a bridge-bar 22' 95 which closes the rear side of the cavity c and is rounded over to a reduced edge 27, Fig. 6, substantially at the level of the throat-plate 8. This bar 22' is formed with spaced clearance grooves 28 for certain feed- 105 ing lugs on the label-pusher to be described.

Overlying and secured to the plate 22 by screws 29 are the flat weak springs 30, the inner downturned and toothed ends 31 of which overhang the end walls 25 of the label-cavity c and are adapted to press lightly upon the upwardly and inwardly folded ends r, Fig. 11, of a severed label s to prevent unfolding of the label-ends after the label has been deposited in the cavity c. The springs 30 are slightly curved, flatwise, Fig. 7^b, so that their free ends will normally assume positions spaced above the upper surface of the plate 22. The toothed ends 31 of the springs 30 are spaced inwardly 110 from the end-walls 25 sufficiently to bear upon the folded over end-portions r of the label at distances inwardly from the lines of fold x, Fig. 11, at the extreme ends of the folded label. The lower plate 22 of the work-holder carries the folding scrolls 32 which turn over the ends of the label when the latter is advanced to the cavity c. 115

The machine is adapted to form labels from a continuous strip of tape t having either selvage or longitudinally folded edges. The tape is carried by a suitable reel (not shown) and passes first through a guideway formed between opposed upper and lower spring-blades 33, 34, Figs. 4 and 120 125 130

13, secured together and to a lateral arm 35, projecting from the slide-block 36, by screws 37. Washers 37' between the spring-fingers 33 and 34 fix them in properly spaced 5 relation to admit the label-strip *t*. At their extremities the springs 33 and 34 bear yieldingly together and serve to put a light tension on the label-strip.

The slide-block 36 is fitted upon the fixed 10 guide-rod 38 which is carried by a bracket 39, the base 39' of which is secured by screws 40 to the edge of the bed 1. Secured to the slide-block 36 by a screw 41 is one end of an anchor-bar 42 the opposite end of 15 which is notched to engage the shank of a screw 43 at the outer end of the bracket 39. When the bar 42 is hooked about the screw 43 it will be evident that the slide-block 36 will, to all intents and purposes, become a 20 fixed part of the bracket 39 and the tape-guiding and tensioning springs 33 and 34 will be fixed relative to the frame of the machine.

The bed 1 is formed beneath and in line 25 with the tape guiding and tensioning springs 33, 34 with a groove or slideway 44 to which is fitted the label feed-slide 45 which is connected by means of a link 46 to one end of the lever 47 pivoted at 48 to the 30 bed 1. The lever 47 is connected at its other end by means of the adjustable link 49 to the work-holder supporting bar 15.

The adjustable link 49 preferably comprises the similar terminal bars 49^a, Figs. 4^a, 35 4^b, which are threaded to receive the screws 49^b, passing through slots 49^c in the connector-bar 49^d; the latter being grooved at 49^e to embrace the reduced shanks 49^f of the 40 terminal bars 49^a. By virtue of this connection it will be evident that when the bar 15 is given a lateral motion, as when sewing along one side of the label, the label feed-slide 45 will be moved in the opposite direction along the guideway 44. As the link 49 45 extends substantially at right angles to the bar 15, the bodily longitudinal motion of the bar 15, as when sewing the ends of the label, will impart no appreciable movement to the label feed-slide.

50 Fixed in a lug 50, Fig. 4, on the label feed-slide 45 is a horizontal pivot pin 51 on which is journaled the tubular hub 52, Figs. 15 and 18, of a three-armed lever, one arm 53 of which projects forwardly and has pivoted to its free end at 54 the label gripper-foot 55 having at its extremities the down-turned toes 56 which at their extreme ends are quite thin but not sharpened. Between the toes 56 is afforded the clearance space 57. Another arm 58 of the three-armed lever projects forwardly and has let into its side face the shank of a shearing blade or knife 59 which is secured in place by a screw 60 under the head of which is also secured the apertured shank of the piercing pin 61.

The third arm 62 of the three-armed lever extends downwardly and is apertured at 62' to freely receive the hooked extremity 63, Fig. 3, of a light rod 64 which extends rearwardly beneath the bed 1 and is fixed by 70 means of the screw 65, Fig. 1, to a lug 66 which extends downwardly through the slot 67 in the bed 1 from a lateral extension 68 of the work-holder supporting bar 15. Thus, when the bar 15 is moved bodily 75 lengthwise of the bed 1, the three-armed lever carrying the label gripper-foot 55, shearing blade 59 and piercing pin 61 will be rocked on its pivot 51.

Cooperating with the shearing-blade 59 is 80 the ledger-blade 69 which is slidably received within a groove or guideway 70, Fig. 8, in the label feed-slide 45 and is yieldably pressed endwise against the cutter-blade by means of the coiled spring 71, Fig. 13, which 85 is received within the aperture 72 in the label feed-slide and presses against the screw 73 carried by the ledger-blade. The spring 71 is backed up by a screw 74 threaded into the aperture 72. The ledger-blade is formed with a clearance aperture 75 for the piercing pin 61. Secured to the label feed-slide, above and in opposed relation to the ledger-blade 69, is a cover-plate 76 formed with an aperture 77 to receive the piercing pin 61. 90 Space is thus provided between the cover-plate 76 and the ledger-blade 69 to receive the tape-tensioning spring blades 33 and 34 as the label feed-slide is moved from the 95 position shown in Fig. 13 to that shown in Fig. 14. This space also serves as a guideway for the end-portion of the label-strip *t* which projects beyond the blades 33 and 34.

The label feed-slide 45 is formed beneath 100 the gripper-foot 55 with grooves 78 which register with the toes 56 of the gripper-foot. It is also formed with clearance grooves 79 which are similar in form and spacing to the grooves 28 in the plate 22. Secured to the slide 45 by screws 80 is a thin label-supporting platform 81 which serves the purpose of holding the label high enough to prevent the possibility of its being caught by the rear edge 27 of the bridge-bar 22' when the label is being advanced to the work-holder. The lower rear corner at the free end of the plate 22 is beveled as indicated at 82, Fig. 5, in order that the plate 22 may slide over the thin platform 81 during the sewing of the first end of the label, at which time the plate 22 is moved toward the slide-way 44 from the position shown in Fig. 5.

A label retainer 83 is provided to control the label after it is released by the gripper-foot and before it is advanced to the work-holder. Secured to the label feed-slide 45 by the screw 84 is one end of an arm 85 the other end of which is forked to provide spaced arms 85', 85'' embracing a vertical pin 86 rising from the bar 15. The label re- 125 130

tainer 83 is in the form of a light spring 5 foot having a smooth under surface and is secured to the forked extremity of the arm 85 by screws 87. When a new label is being fed 10 under the gripper-foot the post 86 strikes the arm 85', Fig. 5, and withdraws the retainer-foot 83 from beneath the gripper-foot. As the parts move to the position shown in Fig. 4, however, the pin 86 strikes the arm 85" and projects the retainer-foot 83 into the clearance space 57, Fig. 15, beneath the gripper-foot 55 and over a label 15 held therebeneath, Fig. 16.

The label is advanced from transfer position, Fig. 16, to the label-receiving cavity *c* of the work-holder by means of a slidably mounted pusher 88, a bottom perspective view of which is shown in Fig. 12. This pusher is preferably made from a sheet-metal plate and comprises the spaced forwardly projecting toes 89, 89 the under surfaces of which are serrated at 90. On its under side at the base of the forwardly projecting toes, the pusher has fixed thereto the label-edge engaging lugs 91. The pusher is formed rearwardly of the lugs 91 with opposed and resilient supporting arms 92 between which is formed a transverse downturned flange 93. The pusher is supported in line with the work-holder supporting bar 15 and is guided in its motion by the latter. The resilient arms 92 extending rearwardly at opposite sides of the bar 15 are secured by screws 94 to the forward ends of the more rigid side-bars 95 which at their rearward ends are joined together by means of a cross-piece 96 grooved at 97, Fig. 17, to fit over the bar 15.

Swivelled to the cross-piece 96 is the post 40 98 which is slotted at 99 to receive the lateral pin 100 carried by the downwardly extending arm 101, Fig. 1, of a three-armed pusher-actuating lever fulcrumed at 102 to a post 103 rising from the bed 1. The three-45 armed pusher-actuating lever comprises a rearwardly projecting arm 104 from which depends a treadle or knee-shift chain 105 passing through the hole 105' in the bed 1.

Referring to Fig. 6, it will be observed 50 that the forward extremity of the bar 15 is reduced in thickness to form a support 106 upon which rests the flange 93 of the pusher, thereby serving to hold the toes 89 above the level of a label *s* held beneath the retainer 83. The front end of the support 106 is beveled at 107. As the pusher 88 is advanced by a pull on the treadle-chain, the toes 89 pass forwardly over the label *s* until the flange 93 reaches the incline 107 whereupon 55 the toothed toes 89 are permitted to descend upon the label as the lugs 91 come into engagement with the rear side edge of the label. Further movement of the pusher carries the label forwardly over the platform 81 and the bar 22' and through the 60 65

folding scrolls 32 which fold the ends of the label upwardly and over the toes 89. As the label is pushed beyond the folding scrolls, the folds *r* pass beneath the downturned free ends of the light fold retaining springs 30 70 which prevent unfolding of the label-ends due to the springy character of the tape, as shown in Fig. 19. When the pusher reaches the end of its advancing stroke, as determined by the adjustable stop-screw 101' on the post 103, which screw is in the path of movement of the lever-arm 101, the lugs 91 register with the wall 24 of the label-cavity *c* into which the label is thus deposited. The front wall 23 of the label-cavity is bevelled 80 at 26, 26, to afford clearance for the tip ends of the pusher toes 89, 89 when fully advanced. As the pusher retracts, the springs 30 assist in stripping the end-folds *r* of the label from the toes 89 of the pusher. The 85 feeding lugs 91 pass along the clearance grooves 28 and 79 during the movement of the pusher.

The label and fabric are preferably 90 pressed firmly together upon the throat-plate 8 by means of a presser-foot 108 which is in the form of an apertured rectangular frame. The side-bars 109 of the foot are formed with downturned flanges 110 which depress the fabric within the label cavity 95 *c* and clamp it firmly upon the label therein. The foot 108 is formed with a shank 111 which slides vertically in a suitable guide-way in the head 112 at the free end of the clamp bracket-arm 113 carried by the bar 100 15. The spring 114 serves to hold the foot 15 yielding but firmly upon the work. Projecting forwardly from the shank 111 of the presser-foot is a lateral pin 115 under which extends the lateral arm 116 fixed to 105 the lower end of the usual presser lifting rod 117 journaled in the head 4. At its upper end the rod 117 carries a collar 118 under which extends the bifurcated end 119 of one arm 120 of a presser-foot lifting lever 110 which is fulcrumed at 121 to a bracket 122, screwed to the bracket-arm 3. Formed rigidly with the arm 120 is a depending arm 123 into the lower end of which is threaded a screw 124 which passes through the slot 115 125 in one end of the link 126 connected at 127 to an arm 128 of the three-armed pusher-actuating lever previously referred to. A leaf-spring 129 secured to the arm 123 bears against the link 126 and serves 120 to retain the pusher-lever arm 101 and pusher 88 in extreme rearward position relative to the bar 15 during the motion of the work-holder in presenting the four sides of the label successively to the needle.

When a pull is exerted upon the treadle chain the first part of the motion of the three-armed lever 101, 104, 128 is utilized to advance the label *s* toward the work-holder. Before the pusher toes have reached the 130

bridge-bar 224, however, the toggle 126, 128 has straightened sufficiently to partially lift the presser-foot 108, thus permitting removal of the work and the consequent clearing of the cavity *c* for reception of the new label being advanced by the pusher.

The machine is preferably equipped with a work-gauge comprising a rod 129 bent to the form shown in Fig. 2 and secured to the post 103 by the wing-nut 130. The gauge 129 is formed with the rearwardly disposed surface 131 around which an edge of work 132 extending from sewing position toward the standard 2 may be bent and lead forwardly along the indicator arm 133 which is graduated and provided with an indicator 134. A work-gauge of this type is particularly desirable for use in the work of sewing button and buttonhole reinforcing patches on the seat flaps of union-garments. The gauge affords convenient means for locating the reinforcements at a uniform distance from the usual back-seam 135 and at right angles to the edge 132 of the seat-flap. The distance between the standard 2 and the sewing point is too short to permit the edge 132 to be extended for measurement in a straight line.

The mechanism adjacent the work-holder is suitably covered by a plate 136 which prevents contact of the work with the moving parts.

A safety device is preferably provided to insure against possible manipulation of the presser-foot lifting and pusher operating mechanism while the machine is running. Fixed to the pivoted stop-motion lever 12 by screws 137 is a laterally extending arm 138, the free end of which is adapted to press against the rearward end of a rod 139 which is slidably mounted in the alined bearing apertures of the spaced lugs 140 and 141 of a bracket 142 fixed to the bracket-arm. A coiled spring 143 surrounding the rod 139 and positioned between the bearing lug 140 and a collar 144 fixed to the rod 139, serves to maintain said rod in engagement with the arm 138. When the stop-motion lever is in running position, Fig. 1, the forward end of the rod 139 projects below the segmental extremity 145 of the arm 104. The extremity 145 is concentric with the pivot 102. It will be evident that a pull upon the treadle chain 105 cannot rock the lever-arm 104 while the stop-motion lever 12 is in running position. When the lever 12 springs to vertical or stopping position, the rod 139 is shifted by the spring 143 until the collar 144 contacts with the lug 141, thereby withdrawing the front end of the rod 139 from its position beneath the segmental portion 145 and permitting actuation of the presser-lifting and pusher-actuating mechanism. It will be clear that when the arm 104 is depressed, the face of the segmental member

145 be moved across the end of the rod 139 and will prevent the shifting of the stop-motion lever 12 to running position.

Operation.

70

Starting with the parts in the position shown in Figs. 4 and 13, it being assumed that the label beneath the gripper 55, Fig. 4, has been fed to the work-holder and a piece of fabric inserted beneath the presser-foot 108, the operator starts the machine. The sewing immediately begins at the point indicated by the needle-hole 7, Fig. 4, and proceeds along the side of the label as the work-holder is moved in step-by-step fashion to the position shown in Fig. 5. During this movement, the label-feed slide is carried to the right from the position shown in Fig. 13, and the label length lying between the ledger-blade 69 and plate 76 remains stationary as the knife 59 and gripper foot 55 move over it to the position shown in Fig. 14. As the sewing proceeds along the first end of the label, the backward movement of the bar 15 exerts a pull upon the rod 64 and rocks the three-armed lever 62, 58, 53, thus projecting the piercing pin 61 through the label strip and causing the knife 59 to sever from the label-strip, the label *s* projecting beneath the gripper-foot 55, Fig. 15. The label is gripped by the foot 55 immediately after it is cut off from the label-strip and the toes 56 of the foot 55 form transverse scorings *v* across the ends of the label as they are pressed tightly into the grooves 78 in the label feed-slide, as shown in Fig. 15.

An adjustable stop 47' mounted on the lever 47 is adapted to strike the base 39' of the bracket 39, as shown in Fig. 5, and serves to prevent overthrow of the label feed-slide 45, thereby securing uniformity in the lengths of the labels cut from the label-strip.

During the second side-stitching operation, the label feed-slide is returned to the position shown in Fig. 13 with the gripper-foot closed and, during the return movement, the piercing pin 61 pulls a label-length of the strip *t* through the tension springs 33, 34. The retainer foot 83 is also swung about its pivot-screw 84 and advances over the label *s* held by the gripper-foot 57.

During the stitching of the second end of the label the forward movement of the bar 15 acts through the rod 64 to lift the piercing pin 61, knife 59 and gripper-foot, as shown in Fig. 16. The sewing is now completed and the machine comes to rest.

Should the operator observe that the sewing is defective and desire to repeat the sewing operation without disturbing the assembled relation of the label and fabric in the work-holder, the anchor bar 42 may be swung from full to dotted line position em-

130

bracing the screw 45* on the label feed-slide 45, Fig. 4, thus connecting the slide-block 36 which carries the tape-tensioning blades 33, 34 with the label feed-slide. If the machine is now operated, the blades 33, 34 will move with the feed-slide and the feed of the tape relative to said feed-slide will be interrupted.

The subsequent operation consists of merely lifting the presser-foot to remove the finished work and insert new work. As previously explained, the action of the operator in lifting the presser-foot serves, through the connection between the presser-foot lifter and the pusher 88, to advance the pusher, thereby carrying the severed and scored label through the folding scrolls and depositing it in the label-receiving cavity in the work-holder.

In the broader aspects of the invention it is immaterial whether the label is sewn to the upper or under side of the work. It is also immaterial, in certain aspects of the invention, whether or not the label ends are folded; the present machine being the first to feed a label-strip, sever labels therefrom at a position spaced from sewing position, feed the severed labels to sewing position and hold them in sewing position until the sewing is substantially completed, irrespective of whether or not the severed ends of the label are folded. The present machine is also the first to prepare and sew labels to the under side of the work; the sewing of button or buttonhole reinforce labels to the under side of the work being particularly desirable in case a chain-stitch forming mechanism is employed, as will be readily appreciated by those skilled in the art.

Having thus set forth the nature of the invention, what I claim herein is—

1. A label cutting, folding and stitching machine having, in combination, stitch-forming mechanism, a workholder having label edge gauging means, means for relatively moving the stitch-forming mechanism and work-holder to sew around a label, means for feeding a label-strip, means for severing a label from said strip, and means for folding the ends of the label and for feeding the folded label to the label edge gauging means in the work-holder.

2. In a label sewing machine, the combination with stitch-forming mechanism, of means for feeding a label-strip, means for severing a label from said strip at a position spaced from sewing position, means for feeding the severed label to sewing position, a work-clamp for holding the label and work in sewing position, and means for relatively moving the stitch-forming mechanism and work-clamp to sew entirely around the label while said label is held by the work-clamp.

3. A label sewing machine having, in com-

bination, stitch-forming mechanism, means for feeding a label-strip, means for severing a label from said strip, means for locating a severed label in sewing position at the under side of the work, and means for relatively moving the stitch-forming mechanism and label locating means to sew around the four sides of the label.

4. A label sewing machine having, in combination, stitch-forming mechanism, a work-holder including upper and lower elements, means for feeding a label-strip, means for severing a label from said strip, means on said lower work-holder element for locating a severed label in sewing position at the under side of the work, and means for relatively moving the stitch-forming mechanism and work-holder to sew around the four sides of the label.

5. A label sewing machine having in combination, stitch-forming mechanism, a work-holder including separable elements, label edge gauging means on one of said elements for locating a label in sewing position, means for feeding a label-strip, means for severing a label from said strip at a position spaced from sewing position, and means for feeding the severed label to the work-holder.

6. A label sewing machine having, in combination, stitch-forming mechanism, a work-holder, means for relatively moving the stitch-forming mechanism and work-holder to sew around a label, means for feeding a label-strip, means for severing a label from said strip, and means for feeding the severed label edgewise to the work-holder while maintaining the same side of the label up-
permost.

7. A label cutting, folding and stitching machine having, in combination, stitch-forming mechanism, a work-holder including separable upper and lower elements, label edge gauging means on one of said elements for locating a label in sewing position, means for relatively moving the stitch-forming mechanism and work-holder to sew around a label, means for feeding a label-strip, means for severing a label from said strip at a position spaced from the work-holder, means for folding over the ends of the severed label, and means for feeding the severed and folded label to the label edge gauging means in the work-holder.

8. A label sewing machine having, in combination, stitch-forming mechanism, a work-holder including separable elements, label edge gauging means on one of said elements for locating a folded label in sewing position, means for feeding a label-strip, means for severing a label from said strip, and means for folding over the ends of the severed label prior to sewing.

9. A label sewing machine having in combination, stitch-forming mechanism, a work-holder including separable elements one of

which is formed with a label-receiving cavity and label edge gauging walls, means for feeding a label-strip, means for severing a label from said strip, and means for folding said label and for feeding the folded label into said cavity.

10. A label sewing machine having, in combination, stitch-forming mechanism, a work-holder, means for relatively moving the stitch-forming mechanism and work-holder to sew around a label, means for feeding a label-strip, means for severing a label from said strip, and a reciprocatory pusher for feeding the severed label to the work-holder.

11. A label sewing machine having, in combination, stitch-forming mechanism, a label-clamp, means for relatively moving the stitch-forming mechanism and label-clamp to sew around a label while held by said clamp, means for feeding a label-strip, means for severing a label from said strip, label-folding means, and means for feeding a severed label to the folding means and thence to the label-clamp.

12. A label sewing machine having, in combination, stitch-forming mechanism, a work-holder, means for relatively moving the stitch-forming mechanism and work-holder to sew around a label, means for feeding a label-strip, means for severing a label from said strip, label-folding scrolls, and a means for feeding a severed label through the folding scrolls and into the work-holder.

13. A label sewing machine having, in combination, stitch-forming mechanism, a work-holder including label locating means, means for relatively moving the stitch-forming mechanism and work-holder to sew around a label, means for feeding a label-strip, means for severing a label from said strip, and a manually operated reciprocatory pusher for feeding a severed label to the label locating means in the work-holder.

14. A label sewing machine having, in combination, stitch-forming mechanism, a work-holder including separable upper and lower elements, manually operated means for separating said elements to open the work-holder, means for relatively moving the stitch-forming mechanism and work-holder to sew around a label, means for feeding a label-strip, means for severing a label from said strip, and means operatively connected to said work-holder for feeding a severed label to sewing position when the work-holder is opened.

15. A label sewing machine having, in combination, stitch-forming mechanism, a work-holder including separable upper and lower elements, folding scrolls carried by said lower work-holder element, means for relatively moving the stitch-forming mechanism and the work-holder to sew around a label, means for feeding a label-strip,

means for severing a label from said strip, and means for feeding a severed label through the folding scrolls and into sewing position in the work-holder.

16. A label sewing machine having, in combination, stitch-forming mechanism, a work-holder including separable upper and lower elements, means for feeding a label-strip, means for severing a label from said strip, means for feeding a severed label to the lower work-holder element in position to be stitched to the lower side of the work, and means for relatively moving the stitch-forming mechanism and work-holder to sew around the four sides of the label.

17. A label cutting, folding and stitching machine having, in combination, stitch-forming mechanism, a work-holder including separable upper and lower elements, means for feeding a label strip, means for severing a label from said strip, and means for folding the ends of a severed label and for feeding the folded label to the lower work-holder element in position to be stitched to the lower side of the work.

18. A label cutting, folding and stitching machine having, in combination, stitch-forming mechanism, a work-holder comprising a lower and an upper element, means for feeding a label-strip, means for severing a label from said strip, means including folding scrolls and a reciprocatory blade for folding over the ends of a severed label and for presenting the folded label to the lower work-holder element with the end-folds uppermost, and means for relatively moving the stitch-forming mechanism and work-holder to sew around the label.

19. A label sewing machine having, in combination, stitch-forming mechanism, a work-holder including a main supporting arm, means for moving said arm lengthwise and sidewise to position the stitches around the label, label-strip feeding means connected with said arm independently of the arm moving means and deriving operative movements from said arm, means for severing a label from said strip, and means for feeding a severed label to the work-holder.

20. A label sewing machine having, in combination, stitch-forming mechanism, a work-holder with means for moving it to position the stitches around the label, label-strip feeding means connected with and deriving operative movements from said work-holder, label severing means also connected with and deriving operative movements from said work-holder, and means for feeding a severed label to the work-holder.

21. In a label machine, in combination, means for feeding a label-strip, means for severing a label from said strip, a gripper for scoring the lines of fold at the end of a severed label, an auxiliary device for hold-

- ing a severed and scored label after it is released by said gripper, a label-folder, and means for feeding a severed and scored label to said folder.
5. 22. A label machine having, in combination, a stationary holder for the end of a label-strip, a reciprocating label feed-slide including a piercing pin for pulling a label-length through said stationary holder, and 10 means for severing a label from said label-strip, said severing means and piercing pin being fixed relatively to one another. 70
15. 23. In a label sewing machine, a work-holder including separable upper and lower elements, label-end folding means, and yielding devices carried by the lower work-holder element for holding the end-folds in place prior to closure of the work-holder. 75
20. 24. In a label sewing machine, a work-holder including separable upper and lower elements, label-end folding scrolls carried by said lower work-holder element, and yielding means carried by said lower element for holding the end-folds in place prior to closure of the work-holder. 80
25. 25. In a label sewing machine, the combination with stitch-forming mechanism and a work-holder, of a pusher adapted to present a label to the work-holder, said pusher having label-edge engaging means, and an overhanging label-face engaging surface, means for moving said pusher toward and away from the work-holder, and means for holding the label-face engaging surface out of contact with a label during the first part of the movement of the pusher toward the work-holder and until said surface is positioned over the label. 85
30. 26. A label sewing machine having, in combination, a frame including a bed, a standard rising from one end of said bed, a bracket-arm supported by said standard, stitch-forming mechanism and a work-holder operating at the opposite end of said bed, and a work-gauge supported above the bed intermediate said work-holder and standard, said work-gauge being formed with a rearwardly disposed surface around which an edge of work extending from sewing position toward said standard may be bent, said work-gauge further including an indicator arm for measuring the work. 90
35. 27. A label sewing machine having a bed, a standard and overhanging bracket-arm, stitch-forming mechanism, a work-holder including separable elements, one of which has a label-positioning cavity, means for relatively moving the stitch-forming mechanism and work-holder to sew around a label, means for feeding a label-strip transversely of the machine bed, means for severing a label from said strip, and a device movable bodily longitudinally of the machine bed for feeding the severed label into the cavity in the work-holder. 95
40. 28. A label sewing machine having, in combination, stitch-forming mechanism, a work-holder, means for imparting stitch-positioning movements to the work-holder in different directions, means connected with and deriving motion from the work-holder when the latter is moved in one direction for feeding a label-strip, means connected with and deriving motion from the work-holder when the latter is moved in another direction for severing a label from said strip, and means for feeding the severed label to the work-holder. 100
45. 29. A label sewing machine having, in combination, stitch-forming mechanism, a stop-motion device for controlling its period of action, a work-holder, automatic means for feeding a label-strip, means for severing a label from said strip, means for positioning the severed label in the work-holder, and manually controlled means for interrupting the feed of the label-strip when it is desired to repeat the sewing operation upon a given label. 105
50. 30. A label sewing machine having, in combination, stitch-forming mechanism, means for feeding a label-strip, means for severing a label from said strip, means for folding over the cut ends of the label, a work-holder having opposed label gauging walls defining a label-receiving cavity, a presser adapted to hold the label and fabric against displacement or distortion during the sewing, and manually controlled means for lifting said presser when the sewing is completed. 110
55. 31. In a label sewing machine, a pair of spaced and opposed folding scrolls and a reciprocatory feeder element for advancing labels through said scrolls, said feeder element having the form of a thin blade with a label-face engaging surface and spaced edge-portions about which the label ends are folded during the movement of said element. 115
60. 32. In a label sewing machine, in combination, stitch-forming mechanism, means for feeding a label-strip, means for severing a label from said strip, a work-holder including a work-holder supporting bar arranged longitudinally of the machine bed, and a label feeder mounted on said bar and adapted to feed a severed label to the work-holder. 120
65. 33. In a label sewing machine, in combination, stitch-forming mechanism, a work-holder, means for feeding a label-strip, means for severing a label from said strip, a feeding element for moving a severed label lengthwise from severing position to transfer position, and another feeding element for moving the label widthwise from transfer position to the work-holder. 125
70. 34. In a label sewing machine, in combination, stitch-forming mechanism, means 130

for feeding a label-strip, means for severing a label from said strip, means for folding the ends of the severed label, a work clamp including separable clamping members, one of which is adapted to engage and hold the severed and folded label throughout the sewing operation, and means for relatively

moving the stitch-forming mechanism and work clamp to sew around the label while held by said clamp. ¹⁰

In testimony whereof, I have signed my name to this specification.

ALFRED GRIEB.
